UNITED STATES PATENT OFFICE

DON W. KING AND FINN T. IRGENS, OF JACKSON, MICHIGAN, ASSIGNEES, BY MESNE ASSIGNMENTS, TO OUTBOARD MOTORS CORPORATION, OF DETROIT, MICHIGAN, A CORPORATION OF MICHIGAN

DRIP PAN FOR OUTBOARD MOTORS

Application filed July 5, 1928. Serial No. 290,305.

The present invention pertains to a novel drip pan for outboard motors, and the principal object is to provide a construction wherein leakage from the carburetor or the breather pipe or both will be discharged overboard rather than on the stern of the boat, although the carburetor and the breather pipe may be disposed directly above the stern.

A device of this character eliminates the fire risk at parts of the boat which ordinarily become soaked with gasoline leaking through the breather pipe and falling on the transom and rear seat. Moreover, the boat is kept in a neater or cleaner condition when such leaking gasoline is discharged overboard.

The object of the invention is accomplished by supporting a drip pan beneath the breather pipe or carburetor, or both, preferably as an integral part of the motor structure, and provided with an outlet so arranged with respect to the usual clamp so that the gasoline discharged over-board when the motor is clamped in the usual manner to the stern of the boat.

The invention is fully disclosed by way of example in the following description and in the accompanying drawing, which shows in elevation an outboard motor equipped with the invention and attached to a boat.

The numeral 1 indicates in general a motor structure of the outboard type having a swivel connection 2 to a clamp 3. The latter has an inclined clamping plane 4 which is brought to bear against the outer surface of the transom 5 of a boat and is held in this position by a screw 6 threaded through the forward end of the clamp and bearing against the forward surface of the transom 5.

To the motor structure is secured a tiller 7 whereby the motor may be swung on a vertical pivot for steering purposes and on a horizontal pivot, around the swivel connection 2, in order to lift the propeller 8 when in shallow water. The latter movement is limited by means of a socket 9 carried by a curved slotted member 10 fixed to the clamp 3.

The motor has the usual breather pipe 11 leading to the carburetor, and this pipe normally lies vertical above the stern of the boat.

It is well known that this relation of parts results in the transom 5 and rear seat 12 becoming soaked with gasoline leaking from the carburetor and this pipe. It will be obvious that these gasoline soaked parts present a dangerous fire risk and also an untidy and disagreeable condition. This difficulty is overcome by supporting a drip pan 13 beneath the pipe in a manner to turn and tilt the motor, preferably as an integral part of the motor structure 1. This pan has an outlet 13 so arranged as to discharge over-board when the clamp is applied to the transom 5. The relation of the outlet may be more specifically described as rearward of the clamping plane 4, the result of which is that the drippings from the outlet fall over-board without striking the transom or rear seat.

Although a specific embodiment of the invention has been illustrated and described, it will be understood that various alterations in the details of construction may be made without departing from the scope of the invention as indicated by the appended claims.

What we claim is:

1. In an outboard motor having a carburetor, a clamp, and a drip pan supported beneath said carburetor and having an outlet, the relation of said carburetor, clamp and drip pan being such that when the clamp is applied to the stern of a boat, the carburetor lies over said stern and the outlet is positioned to discharge outside of said stern.

2. In an outboard motor having a clamp adapted for attachment to the stern of a boat, a carburetor having a part disposed forward of the clamping plane, and a drip pan supported beneath said part and having an outlet adapted to discharge rearwardly of said clamping plane.

3. In an outboard motor having a carburetor, a clamp, and a drip pan integral with said motor supported beneath said carburetor, and having an outlet, the relation of said carburetor, clamp and drip pan being such that when the clamp is applied to the stern of a boat, the carburetor lies forward of said stern and the outlet is positioned to discharge outside of said stern.

4. In an outboard motor having a clamp

adapted for attachment to the stern of a boat, a carburetor having a part disposed forward of the clamping plane, and a drip pan integral with said motor supported beneath said part and having an outlet adapted to discharge rearwardly of said clamping plane.

5. In a swivel outboard motor, a clamp adapted to attach said motor to the stern of a boat, a carburetor having a part forward of the plane of said clamp, and a drip pan supported by said motor arranged to tilt with the motor, and having an outlet adapted to discharge rearward of said clamping plane.

10. In a swivel outboard motor, a clamp adapted to attach said motor to the stern of a boat, a carburetor having a part forward of the clamping plane of said clamp, and a drip pan integral with said motor arranged to turn the motor, and having an outlet adapted to discharge rearward of said clamping plane.

15. In a swivel outboard motor, a clamp adapted to attach said motor to the stern of a boat, a carburetor having a part forward of the clamping plane of said clamp, and a drip pan integral with said motor arranged to turn the motor, and having an outlet adapted to discharge rearward of said clamping plane.

20. In a swivel outboard motor, a clamp adapted to attach said motor to the stern of a boat, a carburetor having a part forward of the clamping plane of said clamp, and a drip pan integral with said motor arranged to turn the motor, and having an outlet adapted to discharge rearward of said clamping plane.

In testimony whereof we affix our signatures.

DON W. KING.
FINN T. IRGENS.
